PLUG COUPLING APPARATUS

Oscar S. Field, Rochester, N. Y., assignor to General Railway Signal Company, Rochester, N. Y.

Application May 23, 1944, Serial No. 536,926

13 Claims. (Cl. 173—328)

1

This invention relates in general to electrical contacting apparatus, and has more particular reference to an improved plug coupling means for use in the provision of quickly detachable electrical connections between two pieces of electrical apparatus.

This application is a continuation-in-part of my co-pending application Ser. No. 361,060, filed October 14, 1940, and entitled Light signals for railroads, now Patent No. 2,376,534, issued May 22, 1945.

One of the objects of the present invention is to provide a plug coupling means in which the socket portion provides a relatively large number of individual and strongly biased metallic contacts for bearing against the inserted plug member.

Another object of the present invention is to provide a large number of socket and plug members within a limited space and so constructed as to provide self-alignment between the socket members and their respective plug members.

A still further object of the present invention is to provide the socket members completely enclosed within a socket board which is arranged to assume a definite predetermined position with respect to the plug board.

Further objects, purposes and characteristic features of this invention will appear as the description progresses with respect to the accompanying drawings, showing in a wholly diagrammatic manner, and in no way whatsoever in a limiting sense one form of the present invention.

With reference to the drawings;

Fig. 1 is a sectional view of the plug coupling means of the present invention taken on line 1—1 of Fig. 2 viewed in the direction of the arrows;

Fig. 2 is a plan view of the inside face of the socket board of the plug coupling means of the present invention;

Fig. 3 is a plan view of the inside face of the plug board of the plug coupling means of the present invention; and

Fig. 4 is a perspective view of one of the socket contactor elements of the plug coupling means of the present invention shown in the other views.

Referring now to the drawings, the plug coupling means constituting the present invention includes a socket board SB shown in Fig. 2 and a plug board PB shown in Fig. 3. Both of these boards are formed of suitable insulating material, such as phenolic condensation product. From these two figures it can be seen that the plug coupling means includes a relatively large

2

number of socket and plug members, and that the position of the inner faces of the boards can be accurately positioned with respect to each other by reason of the beveled outline of the socket board as indicated at 36 in Fig. 1 which is received by the inner face of a depressed portion of the plug board PB. It should be noted that the inner faces of the plug board and socket board do not contact, but are spaced slightly apart, due to the laterally extending lugs 40, three in number, on the socket board, which lugs 40 contact with three inwardly projecting raised pads or portions 41 on the plug board whereby to position the two boards in a vertical plane, regardless of any warping near the central portion of the boards.

The plug board PB has a plurality of plug members mounted thereon, each comprising a threaded headed portion 173 with a squared collar 174 fitting into a corresponding recess in the inner face of the plug board, and clamped thereagainst by a screw 175 received in the socket 173. This screw 175 also fastens a wire, such as wire 176, to the plug member, and after assembly, the wire end terminal can be beaded over, or upset, to form a locking member for the screw. Each plug member includes a plug stem 14 rounded at its end and receivable between the spaced parallel springy fingers 178 of a socket contactor member. This socket contactor member, is shown in perspective in Fig. 4, and includes two side portions with slots therein to form six spring fingers on each side connected at one end by a semi-circular portion 179, and at the other end by a tubular rolled portion 180.

It can thus be seen that these socket contactor members can be readily made by punching their outline and their slots from a suitable flat material, such as phosphor bronze spring material and then formed with the tubular portion 180 followed by the bending of the semi-circular portion 179 and giving an outward slope to the free end. Referring to Figs. 1 and 4, it will be seen that the tubular portion 180 is slightly longer than the semi-circular portion 179 for reasons which will be apparent as the description progresses.

Each of these socket contactor members is receivable in its respective socket or recess 32 in the socket board, and before being assembled therein, a connecting bolt 34 is passed through the tubular portion 180 with a head 183 bearing against one end of the tubular portion, and with the other end extending through a hole 184 in a cover plate 35, which is fastened to the socket

board SB to cover the various sockets or recesses 32 in the board. A nut 186 is received on the outer end of the bolt 34 and serves to clamp the bolt and cover and socket member together. This makes a good electrical frictional connection between the bolt 34 and the socket member, and yet provides a limited amount of spring movement of the contactor member in the slot 32 with respect to the bolt 34 acting as a pivot, to effect the self-centering feature for receiving a plug stem 14. This slight movement of the socket contactor member can occur because its free semi-circular portion 179 does not touch either the cover plate on the one side nor the socket board SB on the other side since the tubular portion 180 is slightly longer, as above mentioned. Suitable nuts 187 are provided for clamping wires 188 to the bolts 34 as shown in Fig. 1.

Threaded studs 190 are provided for fastening the cover 35 in place on the socket board SB and for receiving elongated nuts 191 on the outer end. The stud extends beyond the clamping nut 191 so as to pass through a protective plate 192 and receives nut 193 clamping the protective plate in place. This protective plate 192 is employed to protect the lead wires 188 from interfering with other associated apparatus, and if it is desired to inspect the wire connections, the nuts 193 can be removed without in any way disturbing the clamping together of the plate 35 to the socket board SB.

It should be noted that the sockets 32 in the socket board SB are arranged as shown in Fig. 2, in diagonal positions in offset parallel rows, whereby to economize in space, and to permit a larger number of connectors in a given space than would otherwise be the case. Furthermore, each of the socket contactor members, as shown in Fig. 2, tapers from its tubular end to its other end whereby the plug member 14 which is of a diameter approximately that of the tubular portion 180, acts when it enters into the socket contactor member to spring the two sides apart and cause a tight springy 12 point contact between it and the contactor member. In other words, the spring tension of each contactor member is capable of being distributed between 12 different contacting points on the plug member 14 which is obviously effective to reduce the electrical resistance between the socket contactor member and the plug member. This construction also permits the making of positive electrical contact between the contactor member and its plug member regardless of slight deformities in the contour of the plug member.

It will be noted that the socket contactor members are held in proper vertical positions with respect to the direction of insertion of the plug members by reason of their respective bolts 34, which bolts 34 are held both by the cover 35 and suitable recesses for their square head in the socket board SB as indicated in Fig. 1. Such support for the contactor members is advantageous since they are loosely received in the recesses 32 of the socket board SB and if the contactor members failed to assume proper positions they might not freely receive their respective plug members and some of their contacting strips between the slots and might become bent or broken. In other words, the pivotal mounting of the contactor members of this multiple contact point type is especially advantageous to provide for the proper reception of the plug members.

Referring to Fig. 4, it will be seen that the free end of the contactor member is bent outwardly

and this protrusion of the contactor member serves to engage the side wall of its recess and intensify the spring tension upon the insertion of its plug member.

Referring to Figs. 1 and 2, it will be noted that the holes in the socket board SB are counter sunk so that the rounded plug members 14 may be easily inserted into the socket board upon bringing them into close cooperation. Also, the holes for receiving the plug members are sufficiently large so that the board PB may assume its predetermined position as determined by the beveled edges above described, irrespective of slight variations in the spacing between the plugs. It will also be apparent that the rounded portion of the plug members will co-act with their respective contactor members and cause such contactor members to become aligned in proper positions. In other words, the plug board can assume a predetermined position and the socket contactor members are sufficiently self-aligning to compensate for any variation in the spacing and locations of the respective plugs and yet provide substantial spring tension on each side of a plug member by each of the twelve contacting spring portions 178.

The quick detachable plug coupler described above is very simple and rugged in construction. The plug and socket boards can be readily molded of phenolic condensation product or like material and yet be entirely effective to take predetermined positions with respect to each other. Furthermore, any slight warping of the two boards with respect to each other is ineffective to change their relative positions and does not interfere with the effectiveness of the contact between the plug members and their respective socket contactor members, since such slight variations would not appreciably change the number of contact points between each plug member and its respective socket contactor member. This plug coupling means of the present invention provides unusually good electrical contact between the respective coupling parts, due to the large number of separate points of contact between the springy fingers of the socket members and their respective plug members. Furthermore, the protective plate 192 covering the connecting wires can be removed without disturbing the socket members. Also, the socket members can be readily disconnected and removed for replacing, if necessary, and reassembled without any difficulty due to their self-adjusting characteristics. Obviously such facility is especially desired in connection with inspection and adjustment, or for any other purpose, when such plug coupling means is employed in connection with electrical apparatus where extreme reliability is necessary.

The above rather specific description of the plug coupling means of the present invention as embodied in one particular form is given solely by the way of example, and is not intended in any manner in a limiting sense. It is to be understood that various modifications, adaptations, and alterations, can be applied to meet the requirements of practice without in any manner departing from the spirit or scope of the invention except as limited by the appended claims.

Having described my invention, I now claim:

1. In a plug coupler mechanism, a plug board, a pin-like member in the plug board and projecting inwardly thereof, a socket board, a socket in the socket board, a socket contactor for receiving the plug and loosely received in the socket, a

cover over the socket to hold the contactor in its socket, a post fastened to the contactor and extending through the cover, means clamping the post and cover together, and holding means removably holding the cover on the socket board.

2. In a plug coupler for electrical apparatus and the like, a plug board, a pin-like plug member in the plug board and projecting inwardly thereof, a socket board, a socket in the socket board, a socket contactor for receiving the plug and loosely received in the socket, a cover over the socket to hold the contactor in its socket, a post fastened to the contactor and extending through the cover, means clamping the post and cover together, holding means removably holding the cover on the socket board, a protective plate received on the holding means and spaced from the post, and means on the holding means for removably fastening the protective plate to the socket board.

3. In a plug coupler for electrical circuits, a plug board, a pin-like plug member in the plug board and projecting inwardly thereof, a socket board, a socket in the socket board, a contactor for receiving the plug and loosely received in the socket, a cover over the socket to hold the contactor in its socket, a post fastened to the contactor and extending through the cover, means clamping the post and cover together, holding means removably holding the cover on the socket board, the contactor comprising a wide ribbon of springy conducting metal bent in the form of a V, with one leg of the V bent in a loop for receiving the post, the plug being received between the legs of the V and at a location toward the point of the V.

4. In a plug coupled connector, a plug board, a pin-like plug member in the plug board and projecting inwardly thereof, a socket board, a socket in the socket board, a contactor for receiving the plug and loosely received in the socket, a cover over the socket to hold the contactor in its socket, a post fastened to the contactor and extending through the cover, means clamping the post and cover together, holding means removably holding the cover on the socket board, the contactor comprising a wide ribbon of springy conducting metal bent in the form of a V, with one leg of the V bent in a loop for receiving the post, the plug being received between the legs of the V and toward the point of the V, each leg of the V having a plurality of spaced parallel slots therein, to form a plurality of springy contact means contacting opposite sides of the plug when the coupler is connected.

5. In a plug coupling mechanism for detachably connecting a plurality of electrical circuits, a plug board having a plurality of plug members projecting therefrom, a socket board having a plurality of socket members for receiving said plug members, each of said socket members comprising an elongated contact member constructed to receive and exert contact pressure on the opposite sides of its respective plug member when such plug member is inserted intermediate of its length, said contact member being formed by a multiple number of contacting substantially straight spring portions interconnected at their opposite ends, and means attaching said contact member at one of its ends to said socket board, whereby said contact members are self-aligning with their respective plug members when such said plug board is made to co-act with said socket board.

6. In a plug coupling mechanism for detachably connecting a plurality of electrical circuits,

a plug board having a plurality of plug members projecting therefrom, a socket board having a plurality of contactors for receiving their respective plug members, each of said contactors comprising a wide ribbon of contact spring metal bent in the form of a V with one leg of the V bent in the form of a loop, and a post for passing through said loop of said contactor for mounting said contactor to said socket board, said contactors being located on said socket board to receive said plug members intermediate of their length between the legs of the respective contactors.

7. In a plug coupling mechanism for detachably connecting an electrical circuit, a receiving member comprising an insulating socket board having a recess for loosely receiving a contactor, said contactor comprising a relatively wide strip of contacting spring metal bent in the form of a V with one leg of the V bent in a loop filling the open end of the V, said contactor having slots longitudinally along the legs of the V to form a plurality of individual contacting surfaces for contacting the opposite sides of a plug member when the coupler is connected, a binding post passing through the loop formed in said contactor for mounting said contactor within said recess in a manner to act as a pivot upon which the closed end of the V-shaped contactor can swing, and said insulated socket board having a circular hole slightly larger than the said plug member and centrally located with respect to said recess, whereby the insertion of said plug member through said hole engages said contactor which becomes readily aligned with said plug member by reason of its pivotal support.

8. In a plug coupling mechanism for detachably connecting a plurality of electrical circuits, a plug board having a plurality of plug members projecting therefrom, a socket board having a corresponding plurality of holes for receiving said plug members in relatively predetermined position, and an elongated contact member opposite each hole of said socket board and comprising a slotted spring contacting strip supported at one end on said socket board so as to permit limited movement of its other end in a plane parallel to such socket board and bent to grasp the opposite sides of its respective plug member when it is inserted, whereby a plurality of contacting points are provided between each contactor and its respective plug member, and whereby said contactors are self-aligning with respect to their respective plug members when inserted through said holes in said socket board.

55 9. In a plug coupling mechanism for detachably connecting a plurality of electrical circuits, a plug board having a plurality of projecting plug members, a socket board having a corresponding plurality of holes for receiving said plug members, and a corresponding number of contact members, each being pivotally mounted on that side of said socket board away from said plug board and located beneath its respective hole of said socket board but with the pivot mounting being somewhat off center with respect to that hole so as to be able to swing in a plane parallel with said socket board upon the insertion of its respective plug member, each of said contact members being slotted to provide a multiple number of individual contact points on its respective plug member, whereby the positioning of said plug member in direct cooperation with said socket board causes each of said plug members to pass through its respective hole and make a plurality of wiping contacts with its said contact number.

10. In a plug connector, an insulating member having an elongated recess with an entering circular guide hole located intermediate to the ends of said recess, a contact member formed of a resilient spring metal and having two arm portions extending substantially the length of said elongated recess and beneath said hole with said two arm portions being positioned on opposite sides of the center of said hole, said arm portions being furcated to form a plurality of individual contacting points for each side of a plug member inserted through said guide hole, and means for rigidly supporting said contact member at one end of said elongated recess to maintain said arms in proper positions for the insertion of a plug member.

11. In a plug coupling mechanism for detachably connecting a plurality of electrical circuits, a plug board having a plurality of plug members projecting therefrom, a socket board having a plurality of contactors for receiving their respective plug members, each of said contactors comprising a wide ribbon of contact spring metal bent in the form of a V with one leg of the V bent to form a loop, a post associated with each contactor for passing through the loop of that contactor to act as a support for mounting said contactor to said socket board in a manner to permit the closed end of said V to swing laterally with respect to said socket board, said contactors being located on said socket board to receive said plug members intermediate of their length between the legs of their respective contactors, and three oppositely disposed raised lugs on said plug board to provide a three point limit to the movement of said plug board as it is received by said socket board.

12. In a plug coupling mechanism for detachably connecting a plurality of electrical circuits, a plug board having a plurality of plug members projecting therefrom and having a projecting portion around the outer edge of said plug board with its inner surface beveled, a socket board having a beveled periphery for fitting within the plug board beveled portion and having a plurality of contactors for receiving their respective plug members, each of said contactors comprising a wide ribbon of contact spring metal bent in a

5 form of a V with one leg of the V being longer than the other and shaped in the form of a loop to close the open end of the V, a post on said socket board for each of said contactors for supporting that contactor by passing through its loop, and three oppositely disposed lugs on said plug board for determining its position when received by said beveled socket board.

13. In a plug coupling mechanism for detachably connecting electrical circuits, a plug board having a plurality of plug members projecting therefrom, a socket board having a plurality of contactors for receiving their respective plug members, each of said contactors comprising a ribbon of spring metal bent in the form of a V with one leg of the V being longer than the other and shaped to form a loop within the open end of the V, a post for each contactor adapted to receive the loop of that contactor and to support it with respect to said socket board in a manner to allow the free end of the V to swing with its post acting as a pivot, said socket board having holes therein for receiving said plug members at points intermediate to the length of each of the respective contactors, and said socket board having means supporting both extreme portions of said posts, whereby said contactors are held in vertical positions regardless of the friction established between them and their respective plug members upon coupling and decoupling of the mechanism.
